UNITED STATES PATENT OFFICE.

JACK IMBER, OF LONDON, ENGLAND.

TANK OR RECEPTACLE FOR COMBUSTIBLE OR OTHER LIQUIDS.

1,392,892.

Specification of Letters Patent.

Patented Oct. 4, 1921.

Application filed December 18, 1918. Serial No. 267,359.

To all whom it may concern:

Be it known that I, JACK IMBER, a subject of the King of Great Britain and Ireland, and residing at 162 Worple road, Wimbleton, London, S. W. 19, England, have invented certain new and useful Improvements in Tanks or Receptacles for Combustible or other Liquids, of which the following is a specification.

10 This invention relates to tanks or receptacles for combustible or other liquids and is more particularly intended for petrol or other combustible liquid tanks carried upon aircraft or other vehicles or exposed in other 15 situations where they are liable to be pierced by incendiary or other projectiles.

The object of the present invention is to so improve the construction of such tanks as to prevent or minimize the leakage of 20 liquid in the event of the tank being pierced and to prevent the contents from taking fire should the projectile be of an incendiary nature.

25 The invention consists in a tank or receptacle comprising an inner tubular or other cradle or framework adapted to fit within and conform to the shape of the outer shell or casing of the tank.

30 The invention also consists in a tank or receptacle of the above character, in which the joint of the outer shell or casing is sweated or welded or otherwise formed without the necessity for the employment of rivets or other parts passing through the 35 shell or casing.

The invention also consists in a tank or receptacle of the above character in which the inlet, outlet and other fittings are sweated or welded to the tank and provided 40 with at least two seatings so that in the event of one being destroyed the other will operate to prevent leakage.

45 The invention also comprises the form of tank or receptacle hereinafter more particularly described.

The accompanying drawings illustrate one form of tank in accordance with the invention:—

Figure 1 is a side elevation, half in 50 section;

Fig. 2 is an end elevation, half in section; and

Fig. 3 is a plan, half in section;

Fig. 4 is a section on a larger scale of a fitting; 55

Fig. 5 is a perspective view of the inner cradle, while

Fig. 6 is a detail section through the joint between the edges of the surrounding shell,

Fig. 7 is an enlarged elevation of the partition attachment, 60

Fig. 8 is a detail section through the partition, in advance of the attaching strip,

Fig. 9 is a detail section showing the means for connecting one end or bottom and 65 the shell, and

Fig. 10 is a detail section through one partition.

In carrying my invention into effect in the manner illustrated when forming, for 70 example, a petrol tank for use upon aircraft, I construct the inner cradle or framework preferably of tubular or other light but strong construction, the cradle being formed from outer peripheral members *a* conforming to the shape of the finished tank and cross members or struts *b*, the various members being sweated or welded to one another to form a complete cradle (shown more clearly in Fig. 5) which will fit within and 75

conform to the shape of the outer shell or casing *c*. The latter is wrapped around to give its finished shape and the joint is sweated or welded or otherwise formed (as shown, for example, at *d* in Fig. 6), without the necessity for the employment of rivets or other members passing through the 80 material and one end of the outer casing is then placed in position and flanged over and welded or sweated to the casing proper. 90

The cradle or framework may then be slid into position in the tank and the other end put on in a manner similar to that above described or, if desired, the tank may be formed *in situ* around or upon the cradle 95 or framework. The outer or end peripheral members *a* are provided with tubular rods or elements *a'*, which cross and are secured to said members. These rods serve to reinforce and stiffen the end members and the 100 ends of the receptacle.

When internal baffles or partitions such as *e*, are to be provided in the tank, these may or may not be perforated as shown at *e'*, and may be secured to the framework by 105 being riveted or otherwise secured to clips

f (shown more clearly in Figs. 7 and 8) upon the members of the framework or in any other suitable manner so that the cradle and baffles may thus form an integral whole 5 within the outer shell or casing *c*. The partitions obviously serve to limit the flow of the gasoline or other fluid in any one direction incident to change in positions of the tank, that is such flow is temporarily 10 baffled, and the fluid maintained in a more normal condition. The latter is then covered upon its exterior by means of a suitable covering *g* of rubber or like material, the best composition at present known to 15 me for the purpose consisting of 91 per cent. hard Para rubber, 7 per cent, sulfur and 2 per cent. of magnesia, the covering being vulcanized for, say, 75 minutes under a steam pressure of about 40 lbs. per square inch.

20 It is to be understood that any suitable rubber or like composition may be substituted for that referred to above, and also I may form the cover from a plurality of superposed sheets of any desired thickness.

25 If necessary or desirable, the corners may be reinforced by an additional rubber covering *h*. The construction is such that the tank or receptacle will be of comparatively light but very rigid construction and the 30 inner cradle or framework will form a backing against which the rubber covering may seat itself to form a self-sealing covering in the event of the metal shell *c* of the tank being pierced and will thus prevent leakage 35 of the liquid contents of the tank while at the same time the resilient or elastic covering will return to its seating against the cradle or framework in such a brief space of time that it will be impossible for the 40 contents to ignite in the event of the projectile being of an incendiary character.

In order to provide for the greater security of the tank or receptacle against leakage, all fittings thereon are provided with 45 double seatings so that in the event of one joint giving way there will still be a second joint to prevent leakage.

In one convenient construction illustrated in detail in Fig. 4 in connection with one 50 form of fitting, this may be effected, for example, by having a flanged internally threaded bush *i* sweated upon the inside of the casing *c* and surrounding the aperture for the fitting, and into this I screw a second bush or sleeve *k* which carries the fitting and which makes with the first-mentioned member a joint by means of fiber or other packing. This second bush or sleeve projects beyond the rubber or like covering of 55 the tank and is surrounded by a metal washer *l* which may or may not be corrugated and is forced into close contact with the exterior of such covering or with an additional rubber washer *m* by means of a 60 ring nut or the like screwed upon the outer 65

end of the bush or sleeve, or by means of a flange *n* upon such sleeve so as to form a second joint or seating for the fitting.

If desired, the bush *i* may be so constructed and arranged that it is substantially flush 70 with the inner surface of the metal shell.

The exact arrangement of parts in connection with the fitting may be suitably modified depending upon the character of the fitting concerned as, for example, the 75 washer may be dispensed with and its place taken by a flange upon the ring nut or the like which is threaded upon the outside of the bush or sleeve. In some cases it may be found necessary to employ rivets or the 80 like when forming the joint in the outer shell or casing, but it is preferred, whenever possible, to avoid their use altogether.

It is to be understood that the invention is not to be confined to the foregoing application given by way of example only, nor to the particular details of construction described, as the invention is applicable to any particular form of tank or receptacle whether of circular, elliptical, rectangular or other 90 form in cross-section and whether having plain or convex or other shaped ends or sides, and I modify the form and construction of framework or cradle, the method of securing the baffles when such are employed, 95 and the manner of providing for the double seatings for the various fittings depending upon the type and construction of receptacle to which the invention is to be applied and the purpose for which it is to be employed.

Having now described my invention what I claim as new and desire to secure by Letters Patent is:—

1. A tank for holding combustible liquids 105 comprising a plurality of peripheral members, shaped in correspondence with and adapted to fit in the tank, brace members holding the peripheral members in spaced relation, and angularly related partitions carried by the peripheral members and brace members and formed with openings, and an inclosing shell bearing upon said peripheral members.

2. A tank for holding combustible liquids, 115 comprising a plurality of spaced peripheral members formed of tubular material, the end members of which have portions which cross one another and are secured thereto, spaced vertical struts serving to connect said members and formed of tubular material, horizontal partitions connected with the said members, vertical partitions arranged between the horizontal partitions and connected therewith and with the vertical struts, 120 a shell surrounding said members, ends engaging the end members and having flanges receiving the ends of the shell.

3. A tank for holding combustible liquids, 130 comprising an internal skeleton cage hav-

- ing partitions and defining the size and shape of the tank, a metallic casing inclosing and bearing upon the cage to reinforce said casing, and a rubber envelop closely fitting the casing.
4. A tank for holding combustible liquids, comprising an internal cage having peripheral members connected by struts to define the size and shape of the tank, a metallic casing overlying and bearing upon the peripheral members and struts to reinforce said casing, and a rubber envelop for the casing.
5. A tank for holding combustible liquids comprising an internal skeleton cage defining the size and shape of the tank, a metallic casing inclosing and bearing upon the cage to be reinforced by said cage, and a rubber envelop closely fitting the exterior of the casing.
6. A tank for holding combustible liquids comprising an internal skeleton cage defining the size and shape of the tank, a metallic casing inclosing and bearing upon the cage to be reinforced by said cage, the joint of the material forming the casing being sealed outwardly of the casing without additional fastening means.
7. A tank for holding combustible liquids comprising an internal skeleton cage defin-
- ing the size and shape of the tank, a metallic casing inclosing and bearing upon the cage to be reinforced by said cage, the casing being formed with an opening, and a fitting for said opening including a sealing member arranged within the casing and a second sealing member arranged beyond the rubber envelop.
8. The combination with a metallic container, of an interior reinforcement therefor including vertically and horizontally disposed spaced parallel metallic rods and a protective covering for the container enveloping the latter.
9. A tank for holding combustible liquids comprising an internal skeleton cage defining the size and shape of the tank, a metallic casing inclosing and bearing upon the cage to be reinforced by said cage and a rubber envelop fitting the exterior of the casing.
10. The combination with a container, of an interior reinforcement therefor comprising vertically and horizontally disposed spaced rods and splash plates attached to said rods and a protective covering enveloping the container.

In testimony whereof I have signed my name to this specification.

JACK IMBER.
